UNITED STATES PATENT OFFICE.

EUGENE STILES SCHEBLE, OF FORT WORTH, TEXAS, ASSIGNOR, BY MESNE ASSIGNMENTS, TO S. E. WILMORE, OF NEW YORK, N. Y.

VENDING-MACHINE.

SPECIFICATION forming part of Letters Patent No. 732,786, dated July 7, 1903.

Application filed July 1, 1902. Serial No. 114,010. (No model.)

To all whom it may concern:

Be it known that I, EUGENE STILES SCHEBLE, a resident of Fort Worth, in the county of Tarrant and State of Texas, have invented certain new and useful Improvements in Vending-Machines; and I do hereby declare the following to be a full, clear, and exact description of the invention, such as will enable others skilled in the art to which it applies to make and use the same.

My invention relates to an improvement in vending-machines, and more particularly to coin-controlled vending-machines, an object of the invention being to provide a movable carrier in which goods of different price can be displayed and which can be operated to move any of the goods into position to be removed when the proper coin is dropped into the machine.

20 A further object is to provide improved mechanism whereby the prices for the goods in the several receptacles may vary and provide improved coin-controlled mechanism which will compel the employment of the correct coin before the goods will be ejected.

A further object is to so construct the machine as to prevent any but the proper coin operating to eject the goods and to return a misused coin to the operator in the event of 30 mistake or fraud.

A further object is to provide improvements of this character in which the goods are displayed in separate receptacles above the vending-receptacles, so that the purchaser need make no mistake in his purchase.

40 A further object is to provide an improved vending-machine in which the goods vended are inclosed in envelops or like packages having frangible supports or connections, so that they can be torn free and dropped into easy reach of the purchaser.

With these objects in view the invention consists in certain novel features of construction and combinations and arrangements of 45 parts, as will be more fully hereinafter described, and pointed out in the claims.

In the accompanying drawings, Figure 1 is a view in elevation, illustrating my improvements. Fig. 2 is a view in longitudinal section. Fig. 3 is a horizontal sectional view, and

Figs. 4, 5, and 6 are views of various details of construction.

1 represents a metal casing, which may be hexagonal, as shown, cylindrical, or any other shape desired. In the casing 1 my improved frame or movable receptacle 2 is located and comprises a vertical shaft 3, supported to revolve in a bearing in the bottom of casing 1 and having a cylinder 4 secured thereon some distance above its lower end. 55 This cylinder is provided with a series of radial wings 5, around the upper and lower ends of which rings 6 and 7, respectively, are secured. The spaces between the wings 5 constitute separate receptacles for the 65 goods to be vended, and the goods are carried in envelops or bags 8, perforated at one end to receive a rod 9, hung from upper ring 6, and bent at their lower ends to rest on the lower ring 7 and prevent the escape of 70 the envelops until ejected by the ejector 31, as will be more fully hereinafter explained. On shaft 3, above the receptacles, a conical disk 11 is secured and is provided with radial inclined partitions 12, forming receptacles 13 75 directly above the vending-receptacles for the display of goods similar to the goods in the envelops below and also carry some designation of the price to be paid for such articles. These receptacles 13 can be viewed 80 through a transparent cover 14, secured on casing 1, and through which shaft 3 projects, and is provided with a knob or handhold 15 to be grasped by the purchaser and turn the frame to bring the proper receptacle into operative position, suitable spring dogs or fingers 16 being provided on the receptacles 13 to ride into a notch in casing 1 and temporarily hold the frame in the position desired, thus aiding the purchaser in finding and holding 90 the frame in an operative position.

The front of casing 1 is made with an offset 95 17, in which is contained the coin-controlled mechanism, and a door 18 is provided to permit of ready access to the same when opened. On the top of offset 17 a plate is secured and in which slots 19 and 20 are located and are of just the proper size to receive a one-cent and a five-cent piece, respectively. Beneath these slots guideways 21 are located 100

and are of the proper distance apart to accommodate just the proper coin. Hence should a smaller coin be inserted it will not travel in the guides, but will drop through onto an 5 inclined platform 22, down which it will slide to an open pocket 23 in the offset and in which the goods are delivered, hence returning the coin to the operator. Communicating with these guides 21 and into which they 10 discharge are inwardly-inclined open chutes 24 and 25 of the one-cent and five-cent guides, respectively, and beneath these chutes a hopper 26 is located to receive the coins when deflected thereinto by shields 27 on the upper 15 rings 6 of the movable frame. These shields are located in proper position on the several receptacles, according to the cost of the goods therein contained. For instance, in a receptacle containing one-cent articles the shield 20 will be in such location that when the receptacle is moved to operative position the shield will be in front of chute 24 to deflect the one-cent pieces into the hopper, while the chute 25 for five-cent pieces will be open, and such 25 coins will be returned to the operator, as they will pass entirely over the hopper and fall down inclined platform 22 and into the open pocket 23. When the frame is moved so as to vend a five-cent article, the five-cent chute 30 25 will have a shield 27 in front of it to deflect the five-cent pieces into the hopper, while the one-cent chute 24 will be open and drop the one-cent pieces into pocket 23 if any should be inserted while the frame is in 35 this position.

Below hopper 26 and hinged thereto is a spout 28, held normally in a vertical position by a spring 29, connected at one end to the machine-casing and at its other end to a 40 looped coin-holder 30, secured to spout 28 and having its looped portion located directly below the discharge end of the spout to hold the coins in a vertical position and on the curved face of an ejecting-segment 31. This 45 segment 31 is secured upon a shaft 32, projecting out through the casing and having a lever or arm 33 thereon to operate the segment, as will hereinafter appear, suitable stops being provided to limit the movement 50 of the arm or lever. A clock-spring 34 is provided on shaft 32 to normally hold the shaft in position to "set" the segment, and a ratchet-segment 35 is secured on the shaft near its inner end. A spring-pressed double-acting 55 pawl 36 engages ratchet-segment 35 when moved in either direction—that is to say, when the shaft 32 is turned to move ejector-segment 31 to throw out an envelop the pawl will engage ratchet-segment 35 to prevent 60 the premature return of the ejector; but when the latter has been moved far enough to insure the ejection of the parcel the pawl 36 will pass the end of the series of teeth of the ratchet-segment 35 and said 65 teeth will ride under the pawl and permit the complete return of the ejector-segment to its set position before it can again be operated,

thus preventing more than a single package being ejected when but one coin has been dropped in the machine. To hold the ejector-segment 31 against movement until the coin has been dropped into place, I provide a lug 37 on one side of the segment, which engages the hooked free end of an arm 38, carried by spout 28, so that should any one attempt to move the ejector-segment lug 37 will engage arm 38 and hold the ejector against movement, the hooked end of said arm 38 being moved out of the path of the lug 37 only when the spout 28 and ejector 31 are coupled together by a coin, as presently explained.

On the curved face of ejector-segment 31, at its inner end, a groove or shoulder 39 is provided, whose function is, when a coin is 50 held thereagainst by spout 28 and holder 30, to serve as a coupling and force the spout inward before it rides from beneath the coin, hence moving arm 38 far enough to permit lug 37 to pass over it and not interfere with 55 the operation of the ejector. As the latter is turned it will support the coin until the end of the segment is reached, when the coin will drop into a hopper 40 and be conveyed by a trough 41 to the interior of the casing, from 60 which the coins can be removed through a doorway at the back or sides, as preferred.

To effectually eject the envelops, the inner end of segment 31 is provided with short teeth 43 to engage the envelops, and to 65 strengthen the latter and facilitate their removal I preferably provide them with a cloth or felt paster 44, which is engaged by the teeth 43 and the envelop torn from rod 9. The return movement of the ejector-segment rubbing against the remaining envelops serves to effectually disengage the teeth from the envelop if they should become caught and compel the envelop to drop into the open pocket 23, to be removed by the purchaser. 70 The envelops in one of the receptacles may each contain five one-cent pieces, so that a purchaser can secure change for a five-cent piece to enable him to purchase one-cent articles.

On each of the wings 5 guide-brackets 45 are secured to prevent the operation of the ejector-segment until the receptacle is moved to the proper position, and on these brackets inwardly-projecting fingers 46 are located 75 to hold the envelops back, preventing them from sagging forward to interfere with the perfect operation of the machine.

To prevent a purchaser from dropping a one-cent piece in the machine when the receptacle is in position for a one-cent article and then turn the receptacle to a five-cent article before operating the ejector, I provide the lower ring 7 between each receptacle with a short lug 46, which moves between 80 spout 28 and holder 30, thus striking the coin and knocking it out of position into the pocket below.

It will thus be seen that with my improve-

ments the purchaser can select any goods he desires to purchase, the trays in the top clearly advertising the goods in the receptacles, and when he has decided just what he desires to purchase he turns the frame to bring the proper receptacle into position to be engaged by the coin-controlled mechanism. Then by dropping the proper coin in its proper slot and moving lever 33 an envelope containing the goods desired will be delivered to him in the open pocket below. If the wrong coin is inserted in a slot or if a correct coin is inserted in the wrong slot, they will drop through into the open pocket without operating the machine, or if the receptacle is turned after a proper coin has been dropped the coin will be ejected by means of the fingers 46, as above explained.

A great many changes might be made in the general form and arrangement of the several parts described without departing from my invention, and hence I would have it understood that I do not wish to limit myself to the precise construction set forth, but consider myself at liberty to make such slight changes and alterations as fairly fall within the spirit and scope of my invention.

Having fully described my invention, what I claim as new, and desire to secure by Letters Patent, is—

1. In a vending-machine, the combination with a receptacle for goods to be vended, of a shaft, an ejector-segment on the shaft, a hinged coin-spout above the segment, a holder to couple the segment and spout together by means of the coin, a hooked arm on the spout to be engaged by a lug on the segment and hold the latter against movement until coupled to the spout by the coin, and means for turning the shaft to operate the ejector-segment and eject the goods.

2. In a vending-machine, the combination with a receptacle for goods to be vended and an ejector to eject them, of coin-controlled mechanism for the ejector comprising a coin-spout, a holder below the spout to hold the coin upon the ejector, a shoulder on the ejector

to temporarily force the coin and spout in one direction and an arm to hold the ejector but moved out of engagement when a coin moves 50 the spout and ejector together.

3. In a vending-machine, the combination with a casing and a movable frame therein comprising a series of receptacles for goods of different price, of a coin-controlled ejector for 55 the goods in any of said receptacles, incomplete coin-guides to direct the coins into operative position, and shields carried by the receptacles to complete the proper coin-guide according to the price of the articles contained 60 therein.

4. In a vending-machine, the combination with a casing and a movable frame therein comprising a series of receptacles for goods of different price, of a coin-controlled ejector for 65 the goods in all of the receptacles when moved into position, an open pocket into which the goods are ejected, incomplete guides for various coins adapted while incomplete to direct the coins to the open pocket, and shields carried by all of the receptacles to complete the proper coin-guides, according to the price of the articles contained therein to permit the operation of the ejector.

5. In a vending-machine, the combination 75 with a movable frame containing a series of receptacles for goods of different price, of a coin-controlled ejector for all of said goods, coin-guides of just the right size to receive the proper coins, an open pocket into which the 80 goods are discharged and into which a coin smaller than a guide will fall, and shields carried by all of said receptacles to complete the proper coin-guide and direct the coin into operation and a guide for the coin, after operation of the ejector, to direct the coin into a suitable receptacle.

In testimony whereof I have signed this specification in the presence of two subscribing witnesses.

EUGENE STILES SCHEBLE.
